CHILD'S GARMENT

Mathilda R. H. Whipple, Rapid City, S. Dak.

Application February 26, 1941, Serial No. 380,666

3 Claims. (Cl. 2—80)

This invention relates as indicated to children's garments, and more particularly to garments adapted for use as play suits and sun suits on children of "toddling" age, i. e., children who are learning or have just learned to walk.

While various types of garments are now on the market for children of this age, they generally embody forms of construction which either render the same a nuisance in dressing the child or complicate the necessarily frequent laundering and ironing. Buttons, elastic inserts, and the like, are to be avoided if possible since they are subject to injury or loss during laundering and complicate the ironing whether done by hand iron or any of the commercial ironers. Such problems become of considerable importance when it is necessary to launder a large number of such garments a week.

It is, therefore, a primary object of my invention to provide a child's buttonless combination garment which may be quickly and securely fixed on the child and which is adapted to be quickly laundered and ironed.

Another object is to provide such garment which will maintain its proper position on the child and yet permit great freedom of movement.

A further object is to provide such garment which may be adjusted to accommodate it to the growth of the child.

Still another object of my invention is to provide means for holding the child still during the dressing operation.

To the accomplishment of the foregoing and related ends, said invention, then, consists of the means hereinafter fully described and particularly pointed out in the claims.

The annexed drawing and the following description set forth in detail certain means embodying the invention, such disclosed means constituting, however, but one of various forms in which the principle of the invention may be used.

In said annexed drawing:

Fig. 1 is a front perspective view of one embodiment of the garment of my invention;

Fig. 2 is a rear perspective view of such garment;

Fig. 3 is a fragmentary rear elevational view of the garment but showing the shoulder straps not yet tied through the rear loop;

Fig. 4 is an enlarged detail view of the rear loop through which the ends of the shoulder straps are adapted to be tied;

Fig. 5 is a detail view of another embodiment of my invention wherein an opening on the order

of a large button hole is employed in lieu of such loop;

Fig. 6 illustrates the manner of tying the ends of the shoulder straps through such opening; and

Fig. 7 is a sectional view taken through one of the shoulder straps along the line 7—7 on Fig. 3, illustrating the manner in which the material is doubled over to form such strap.

Referring now more particularly to such drawing and especially Figs. 1 and 2, the garment of my invention comprises a chest portion 1 and step-in trunks 2 attached along the front of the waist line to the bottom of said chest portion. Shoulder straps 3 and 4 start from the belt 5 and extend from the respective upper corners of such chest portion, crossing each other at the rear. Such straps are formed of doubled material, with stitches 6 along each edge (see Fig. 7) and are desirably about an inch wide. Such straps are relatively easy to tie and untie and likewise offer no difficulties in ironing. To prevent the straps from slipping from the child's shoulders, one strap passes through an opening 7 in the other strap at the point of crossing, such opening being on the order of a button hole and about $1\frac{1}{2}$ inches long. For most children of the age for which the garment is designed, this opening will be placed in the strap at a point about 10 inches from the top of the chest portion.

A loop 8 made of a cloth strap similar to such shoulder straps is provided attached to the trunks centrally of the upper rear edge thereof, through which such shoulder straps are adapted to be tied, as illustrated in Figs. 1 and 2. Such loop will desirably be of ample size to permit the insertion of at least two fingers therein, not only to facilitate the passage of a shoulder strap therethrough but also to serve as a handle to keep the child under control during the dressing operation. In fact, in a preferred embodiment of my invention the loop may include $9\frac{1}{2}$ inches of material and extend about $2\frac{1}{2}$ inches above the top of the belt 5. One end of such loop will desirably be tucked in under such belt portion as shown in Fig. 4 and an inner loop 9 is also desirably provided formed by stitching 10 which may be ripped out to extend the length of the main loop as it becomes necessary to adapt the garment to the increased height of the child, children of the age for which this garment is particularly designed growing much more rapidly in length than in girth. As best shown in Fig. 3, one-half of the loop is preferably slightly offset relative to the other half to facilitate insertion

of the fingers therein. It is, of course, obvious that more than one small inner loop may be employed to allow for progressive lengthening.

In the embodiment of my invention illustrated in Figs. 5 and 6, a large button hole 11 is employed in place of the loop 8, being a simplified form of construction which, however, does not afford all the advantages of the construction above described, particularly in not being adapted to serve as a handle nor being in any way extensible to accommodate growth of the child. Of course some adjustment is possible by tying the shoulder straps therethrough somewhat nearer their ends. It will be noted that, if desired, the rear loop may be of such dimensions as to permit the tying of the shoulder straps therethrough adjacent the point of crossing of such straps and thus prevent undue extension of one shoulder strap at the expense of the other as the child plays.

Other modes of applying the principle of my invention may be employed instead of the one explained, change being made as regards the means herein disclosed, provided the means stated by any of the following claims or the equivalent of such stated means be employed.

I therefore particularly point out and distinctly claim as my invention:

1. A child's buttonless combination garment, comprising a chest panel portion, step-in trunks attached along the front of the waist line to the bottom of said chest panel portion, crossed shoulder straps extending from the respective upper corners of said chest panel portion, one of said straps passing through a hole in the other of said straps at the point of crossing, a loop attached centrally of the upper rear edge of said trunks, said loop being of sufficient dimensions to permit the insertion of at least two fingers therein and having one half of the loop slightly offset rela-

tive to the other half of said loop, and an inner loop formed by doubling back a portion of the material of said first-named loop by the opening of which the dimensions of such first-named loop may be increased when made necessary by the growth of the child.

2. A child's buttonless combination garment, comprising a chest panel portion, step-in trunks attached along the front of the waist line to the bottom of said chest panel portion, crossed shoulder straps extending from the respective upper corners of said chest panel portion, one of said straps passing through a hole in the other of said straps at the point of crossing, a loop attached centrally of the upper rear edge of said trunks, said loop having one half of the loop slightly offset relative to the other half of said loop, and an inner loop formed by doubling back a portion of the material of said first-named loop by the opening of which the dimensions of such first-named loop may be increased when made necessary by the growth of the child.

3. A child's buttonless combination garment, comprising a chest panel portion, step-in trunks attached along the front of the waist line to the bottom of said chest panel portion, crossed shoulder straps extending from the respective upper corners of said chest panel portion, one of said straps passing through a hole in the other of said straps at the point of crossing, a loop attached centrally of the upper rear edge of said trunks, said loop being of sufficient dimensions to permit the insertion of at least two fingers therein and an inner loop formed by doubling back a portion of the material of said first-named loop by the opening of which the dimensions of such first-named loop may be increased when made necessary by the growth of the child.
